(57) **CLAIM**

The ornamental design for a solar powered golf caddy, as shown and described.

DESCRIPTION

FIG. 1 is a front elevational view of a solar powered golf caddy showing my new design;

FIG. 2 is a rear elevational view thereof;

FIG. 3 is a side elevational view thereof, the broken lines are for illustrative purposes only and form no part of the claimed design;

FIG. 4 is a side elevational view thereof showing the golf caddy in a solar charging position;

FIG. 5 is a top and front perspective view thereof; and,

FIG. 6 is a rear perspective view thereof.
